UNITED STATES PATENT OFFICE

EDWIN ARCHER TURNER, OF NEW YORK, N. Y., ASSIGNOR TO THE STANDARD STOKER COMPANY, INCORPORATED, A CORPORATION OF DELAWARE

LOCOMOTIVE CAB UNDERFRAME

Application filed November 29, 1930. Serial No. 498,987.

This invention relates generally to locomotive construction and more particularly to improvements in the construction of locomotive cab underframes.

5 An object of the invention is the provision of a new and improved locomotive cab underframe construction whereby the design is materially simplified, the number of separable parts is reduced, cost of construction 10 and maintenance is lowered and a more durable and lighter construction is produced.

It is a further object of the invention to provide in a stoker equipped locomotive, a construction wherein the stoker fuel delivery conduit is formed as an integral unit with the locomotive cab underframe, or as a detachable unit if preferred.

It is a further object of the invention to provide in a stoker equipped locomotive, a 20 construction wherein the locomotive cab underframe is formed with an upstanding flange, the upper portion of which is apertured to form a firedoor ring and the lower portion thereof is apertured to receive a 25 stoker fuel conduit.

It is a further object of the invention to provide in a locomotive, a novel cab underframe having formed therewith means for supporting a locomotive cab.

30 To the above and other ends my invention consists in a certain novel features of construction, and arrangement of parts herein-after more fully described and illustrated in the accompanying drawings, in which

35 Fig. 1 is a central longitudinal section through the rearward portion of a locomotive showing the invention in similar section;

Fig. 2 is a sectional view on the line 2—2 40 of Fig. 1;

Fig. 3 is a sectional view on the line 3—3 of Fig. 1;

Fig. 4 is an isometric view of the novel cab underframe;

45 Fig. 5 is a fragmentary view similar to Fig. 1 showing a modified form of the invention; and

Fig. 6 is a plan view on the line 6—6 of Fig. 5.

50 In the drawings the locomotive is indicat-

ed generally by the numeral 10 and includes the main frame 11, the cab 12 and cab deck 13. At 14, there is shown the backhead of the firebox 15, constituting a water leg of the boiler 16. A portion of the grate of the firebox is shown at 17. The backhead 14 has an opening 18 therethrough arranged to form both a hand firing opening and a stoker firing opening. The cab 12 is supported by the cab underframe 19 which will be hereinafter described more in detail.

Referring more particularly to Figs. 1 to 4 inclusive, the cab underframe 19 is shown as comprising the horizontal plate member or floor 20 which is cored or apertured as at 21 in 35 order to reduce the weight thereof, and recessed at 22 to conform with the shape of the rearward portion of the boiler 16. Formed with the forward edge of the plate member 20 and located centrally thereof is an upstanding flange 23 extending above and below the horizontal plane of the plate member 20 and attached by suitable means to the backhead 14 at the marginal edges of the opening 18. The cab underframe 19 is provided with the integrally formed upstanding flanges 24 and 25, to which are attached the cab side sheets 26 and 27 respectively; the upstanding flanges 28 and 29 to which is attached the cab rear sheet 30; and the upstanding flanges 31 and 32 to which is attached the cab front sheet 33. The cab underframe is provided with an integrally formed depending flange 34 at its rearward end and an integrally formed flange 34a depending from the cab underframe plate 35 member 20 adjacent the backhead 14 and arranged for attachment thereto, whereby the cab under frame is securely attached to the boiler backhead. Additional depending integrally formed flanges 35 and 36 may be provided for further securing the cab underframe from the boiler 16.

The boiler 16 is supported at its rearward end from the main frame 11 by the yieldable plate 37, which is attached at its upper end to the boiler mud ring 38. A flexible plate 39 attached at its upper end to the flange 34 supports the cab under frame 19 at its rearward end from the main frame 11. It will thus be seen that the cab underframe is free to move 100

with the backhead as it expands and contracts by reason of its being flexibly supported from the main frame 11.

A stoker conduit 40 is formed, preferably although not necessarily, with the cab underframe 19 and its mouth portion 41 may be formed integral with the lower portion of the flange 23. The upper portion of the flange 23 is apertured at 42 to form a firedoor ring 43 and the lower portion thereof is arranged to form a closure for the lower portion of the opening 18 in the backhead 14. The mouth portion 41 of the stoker conduit extends through the plane of the flange 23, into the firebox 15 and opens upwardly therein to deliver fuel at a height above the normal level of the fire. An opening 44 in the cab underframe 19 communicates with the stoker conduit 40, and a corresponding opening in the cab deck 13 permits easy access to the stoker conduit 40 for purposes of inspection and permits the fireman to observe the rate of delivery of the fuel. A grating 45 constituting a portion of the cab deck forms an apertured cover for the opening to the stoker conduit 40.

Fuel is advanced through the stoker conduit 40 to the firebox by the screw conveyor 46. Suitable means is provided for delivering fuel from a source of supply, as a locomotive tender, not shown, to the stoker conduit 40 including a telescoping conduit 47, the forward portion of which is universally connected to the rearward end of the stoker conduit 40 and a screw conveyor 48 mounted in the telescoping conduit 47 and universally connected to the screw conveyor 46.

The fuel distributing mechanism comprises a plate 49 which extends laterally from the upper margin of the stoker mouth portion 41 and is preferably level, serving as a table over which the fuel issuing from the mouth portion 41 may be swept by steam jets 50 issuing from the nozzle 51 located in the recess at the upper rearward side of the mouth portion 41.

In Figs. 5 and 6 is illustrated a modified form of the invention in which the cab underframe floor forms the cab deck proper, and in which the mouth portion of the stoker conduit is made removable. As in the preferred modification a rearward section 52 of the stoker conduit 53 may be formed integral with the cab underframe 19 and the flange 23, but the mouth portion 53, which is in effect a continuation of the rearward conduit section 52, can be detached if found destroyed by the heat of the fire or worn by the passage of fuel therethrough. The mouth portion 54 has formed therewith a laterally extending flange 55 which when applied is received in the seat 56 formed by the U-shaped lug 57 formed vertically on the flange 23 adjacent the opening formed by the stoker conduit 53 through the plane of the flange 23.

It is believed evident from the drawings and the description that my invention pro-

vides a rigid durable structure which is simple in design and forms a stronger construction than the same weight of metal in a fabricated structure and by reason of the increased strength permits the use of a lighter structure than is possible with a fabricated structure. There are no joints to work loose and there is no maintenance after the structure is once assembled into a locomotive. Furthermore, it permits a more direct delivery of the fuel through a forward conduit section free from abrupt angles or obstructive curves such as may pulverize lump fuel in its conveyance to the firebox.

I claim:

1. A locomotive cab underframe having a stoker conduit section formed integral therewith and an upstanding flange formed therewith, a portion of said flange extending above the floor of said underframe and a portion thereof extending below the floor of said underframe, said upper portion of said flange being apertured to form a firedoor ring and said lower portion of said flange being apertured to receive said stoker conduit. 60

2. A locomotive cab underframe having a stoker conduit section formed integral therewith.

3. A locomotive cab underframe including a floor portion having a stoker conduit section formed integral therewith and having an opening in said floor portion communicating with said conduit section. 95

4. A locomotive cab underframe having a stoker conduit section formed integral therewith, said section protruding beyond the forward central portion of the underframe and opening upwardly. 100

5. A locomotive cab underframe having a firedoor ring and a stoker conduit section formed integral therewith. 105

6. In combination, a locomotive cab underframe having a stoker conduit formed integral therewith, and a mouth portion for said conduit detachable from said underframe. 110

7. In a locomotive, in combination, a firebox having a backhead with a firing opening therein, a cab, an underframe for said cab, and a stoker conduit formed integrally with said underframe and communicating with the firebox through said firing opening. 115

8. In a locomotive, in combination, a firebox having a backhead with a firing opening therein, a cab, a unitary underframe for said cab, and a stoker conduit section detachably secured to said underframe and arranged to deliver fuel to the firebox through said firing opening. 120

9. In a locomotive, in combination, a firebox having a backhead with a firing opening therein, a cab, an underframe for said cab, a stoker conduit formed integrally with said underframe and communicating with the 130

firebox through said firing opening, and an upstanding flange formed integrally with said underframe and surrounding said conduit section, said flange overlapping the firing opening of the backhead and being apertured at its upper portion to permit hand firing of fuel from the cab through said firing opening.

10. In a locomotive having a main frame and a firebox the combination of a backhead, a cab, an underframe for said cab, a depending flange formed integrally with said underframe for attachment to said backhead, upstanding flanges formed integrally with said 15 underframe at its marginal edges, said cab being supported from said underframe by attachment to said upstanding flanges, a depending flange formed integrally with the rearward end of said underframe for attachment thereto of means for supporting the rearward end of said underframe from said main frame.

11. A locomotive cab underframe having a stoker conduit section formed integral therewith and a spherical flange depending from and formed with said underframe forming the rearward end of said conduit section.

12. A locomotive cab underframe including a cored floor portion, a stoker conduit section formed integral with said floor portion, openings in the top wall of said conduit and said floor portion respectively providing access to said conduit through the opening in said floor.

35 13. In a locomotive having a main frame and a firebox, the combination of a backhead having a firing opening therein, a cab, an underframe for said cab, a depending flange formed integrally with said underframe for 40 attachment to said backhead, a stoker conduit formed integral with said underframe communicating with said firing opening, upstanding flanges formed integral with the marginal edges of said underframe, said cab 45 being supported from said underframe by attachment to said upstanding flanges, and a depending flange formed integrally with the rearward end of said underframe for attachment thereto of means for supporting the 50 rearward end of said underframe from said main frame.

14. As a new article of manufacture a locomotive cab underframe having a stoker conduit section formed integral therewith, an 55 upstanding flange formed therewith, a portion of said flange extending above the floor of said underframe and a portion thereof extending below the floor of said underframe, said upper portion being apertured to form 60 a firedoor ring and said lower portion being apertured to receive said stoker conduit, upstanding flanges formed integrally with said underframe at its marginal edges, and a depending flange formed integral with the rear- 65 ward end of said underframe.

15. A locomotive cab frame member having a stoker conduit section formed integral therewith.

16. A locomotive cab frame member having a stoker conduit section formed therewith and having an opening communicating with said conduit section.

In testimony whereof I affix my signature.
E. ARCHER TURNER.
